FILLING APPARATUS FOR VOLATILE LIQUIDS WITH VAPOR RETURN CONDUIT

Filed Nov. 29, 1943

UNITED STATES PATENT OFFICE

2,439,887

FILLING APPARATUS FOR VOLATILE LIQUIDS WITH VAPOR RETURN CONDUIT

Peter M. Elliott, Toronto, Ontario, Canada, assignor to Oil Distribution Appliances Limited, Toronto, Ontario, Canada

Application November 29, 1943, Serial No. 512,181

4 Claims. (Cl. 222—118)

1

This invention relates to filling apparatus, particularly apparatus for filling tank waggons with gasoline or other volatile liquids from a tank.

The main object of the invention is to effect a saving in gasoline by recovering a substantial portion of the gasoline which normally is lost in escaping fumes. A further object is to provide improved means for raising and lowering the nozzle. A further object is to devise filling apparatus in which the danger of fire or explosion is reduced to a minimum.

The invention is hereinafter more particularly described and is illustrated by way of example in the accompanying drawings in which

Figure 1 is a front elevation with parts broken away to show the construction thereof;

Figure 2 a side elevation, likewise with parts broken away; and

Figure 3 an enlarged vertical section on the line 3—3 in Figure 1.

In the drawings corresponding numerals refer to corresponding parts in the different figures.

The discharge spout or nozzle 1 is connected with two liquid lines or conduits 2, 2, controlled by a valve 3. Within the nozzle is a fume tube 4 for the return fumes. This runs up in front of the nozzle, and is provided with a sight-glass 5. In Figure 2 the nozzle is partly broken away to show the tube 4. See also Figure 3. A vertical rigid constant length pipe 6 which is substantially in alignment with the nozzle 1 extends upwardly between the vertical portions of the two gasoline inlet pipes 2, 2. The lower end of the pipe 6 communicates with fume tube 4 through drip chamber 37.

The upper end of the pipe 6 connects with a fume conduit 22 which runs to a point adjacent the top of the supply tank 23. A pressure relief valve 26 is provided in the fume conduit at its connection with the tank 23.

The liquid conduits 2, 2 run to a point adjacent the bottom of the tank 23, and both the fume conduit and the liquid conduits include a loose section of flexible hose to permit them to be moved up and down and to and from the tank.

The connection between the lower end of the pipe 6 and the nozzle is a ball and socket joint 6^a which permits movement of the nozzle to adjust itself to the angle of the tank wagon so that the gasket 4^a will fit closely to the opening in the tank wagon.

The following mechanism is provided for raising and lowering the nozzle. A sleeve 7 extends around the pipe 6 and has a rack 7^a formed in the side thereof, or the rack teeth may be formed

2

directly on the side of the pipe 6 and extending longitudinally thereof. A gear A is rotatable by means of a chain 20 and pulley 21 and rotates gear B which in turn rotates gear C which engages the rack 7^a and moves it up and down.

The vertical pipe 6 and its sleeve 7 slide in a fixed guide 8 mounted on the carriage 9 and is normally spring supported by means of the cross-bar 10 which is secured to the lower end of the sleeve 7 and which is connected by means of chains 11 to recoil springs 12 in casings 13. In Figure 2 the casing 13 is partly broken away to show the chain 11 and the spring 12. The springs 12 normally counterbalance the weight of the nozzle, the liquid conduits 2, and the pipe 6. The rotation of the gear wheel C will force the sleeve downwardly against the tension of the springs 12 to force the nozzle into the opening in the tank wagon. The sleeve 7 is slidably mounted on the pipe 6 and a spring 13^a extends around the pipe 6 and engages the sleeve 7 and the upper end of the nozzle structure 6 and acts as a buffer to break the jar when the nozzle is pushed into the opening in the tank car or wagon.

The carriage 9 is provided with wheels 24 which run on tracks 25 whereby the filling apparatus may be moved to and from the tank 23 to a point over the filling opening of the tank wagon.

An important feature of the invention is the arrangement of the fume tube 4. Details of its construction are shown in Figure 3. Openings 4^b admit the fumes from the tank wagon into the fume tube 4. A float 27 fits in the bottom of the fume outlet over the opening 4^c provided with an upwardly extending rod 27^a which has a ball 27^b on its upper end at the bottom of the sight-glass 5. When the liquid in the wagon reaches the bottom of the nozzle the float will rise and the ball 27^b will go up in the sight-glass indicating to the operator that the wagon tank is full.

A pressure regulator valve 28 rests on a seat 29 to control the pressure at which fumes will escape. This valve has a stem 28^a which extends 45 through a guide 30 to a weight chamber 31. Weights 32 are placed over the stem 28^a to provide the necessary resistance to the pressure. Additional weights may be placed on the valve as required to increase or decrease the pressure at 50 which the fumes will escape. The weight required will vary according to the pressure under which the liquid is being supplied to the wagon tank, it being essential that a greater pressure be required to lift the valve 28 to avoid too great a loss of fumes. The exact weight required can

readily be determined by one skilled in the art, if necessary, by experiment.

A screw cap 33 encloses the chamber 31, and has a hole therein through which extends a link 34 connected to the valve stem 28^a and a cam 35 from which extends a lever 36. By pulling down the lever the valve 28 may be lifted from its seat to permit liquid which has accumulated in the drip chamber 37 to flow down to the nozzle.

The drip chamber collects liquid which drains down the pipe 6. The valve 28 is closed when the nozzle is not being used so that liquid which drips down is caught and does not drip out of the nozzle.

A scrubber 38 is located at the bottom of the vertical pipe 6. This comprises an inverted cone having a plurality of perforations therein for the fumes to pass through. A pressure relief valve 39 is provided for releasing pressure in the fume tube 4 below the valve 28. A spring normally closes this valve but it may be opened by pressing it inwardly.

Fumes are carried up the fume tube 4 directly from the interior of the tank wagon. The pipe forms a sort of tower or column, and during the passing of the fumes up the pipe liquid forms and drops down to the drip chamber and from thence through fume tube 4 in the nozzle into the wagon tank. What fumes escape through the tank relief valve 26 have had most of the excess liquid removed therefrom, and there is great saving in gasoline.

It is thought that the construction and use of the invention will be apparent from the above description of the various parts and their purpose. It is to be understood that the form of my invention herewith shown and described, is to be taken as a preferred example of the same, and that various changes in the shape, size and arrangement of parts may be resorted to, without departing from the spirit of my invention, or the scope of the subjoined claims.

What I claim as my invention is:

1. Filling apparatus for filling tank waggons and the like from a tank comprising a liquid conduit for carrying liquid from the tank, a liquid discharge nozzle connected to the liquid conduit, a fume tube forming part of said nozzle for carrying off fumes, a vertical pipe communicating with the fume tube, said vertical pipe forming a tower or column where liquid tends to separate from the gases and run back to the nozzle; and means for raising and lowering the nozzle including a support, gear means on said support, a sleeve slidably on said vertical pipe, a spring surrounding said pipe and engaging the lower end of the sleeve and the nozzle, and a rack on said sleeve engaging said gear means.

2. Filling apparatus for filling tank waggons and the like from a tank comprising a liquid conduit for carrying liquid from the tank, a liquid discharge nozzle connected to the liquid conduit, a fume tube forming part of said nozzle for carrying off fumes, a vertical pipe communicating

with the fume tube, said vertical pipe forming a tower or column where liquid tends to separate from the gases and run back to the nozzle, a drip chamber below the vertical pipe, and a check valve between the drip chamber and the fume tube adapted to close and retain condensate in the drip chamber when the filling apparatus is not in use and to open to admit fumes from the fume tube when pressure in the tank reaches a predetermined point.

3. Filling apparatus for filling tank waggons and the like from a tank comprising a liquid conduit for carrying liquid from the tank, a liquid discharge nozzle connected to the liquid conduit, a fume tube forming part of said nozzle for carrying off fumes, a vertical pipe communicating with the fume tube, said vertical pipe forming a tower or column where liquid tends to separate from the gases and run back to the nozzle, a drip chamber below the vertical pipe, a check valve between the drip chamber and the fume tube weighted to control the pressure at which fumes passing into the fume tube may be admitted to the drip chamber and the vertical pipe, and manually operable means for opening said check valve to permit liquid which has accumulated in the drip chamber to flow into the fume tube.

4. Filling apparatus for filling tank waggons and the like from a tank comprising a liquid conduit for carrying liquid from the tank, a liquid discharge nozzle connected to the liquid conduit, a fume tube forming part of said nozzle for carrying off fumes, a vertical pipe communicating with the fume tube, said vertical pipe forming a tower or column where liquid tends to separate from the gases and run back to the nozzle, a drip chamber below the vertical pipe, a pressure valve between the drip chamber and the fume tube, an aperture extending through the wall of the fume tube, and a manually operable relief valve in said aperture for relieving the pressure below said pressure valve.
